UNITED STATES PATENT OFFICE.

LOUIS HALPERN, OF NEW YORK, N. Y.

VIBRATING ROLLER.

Application filed September 1, 1927. Serial No. 216,973.

My invention relates to rollers suitable for use in printing presses and refers particularly to vibrating inking rollers for such described use.

- 5 In roller printing presses it is essential that the ink be distributed evenly over the inking roller and to accomplish this purpose it is usual to have a plurality of inking rollers rotatable by their movement over the inking 10 plate, combined with which is a roller revolvable by its abutment upon the inking rollers and having a transverse movement along the faces of the inking rollers in order to more evenly distribute the ink thereon. 15 Such rollers are known as the vibrating rollers.

Among the desirable features which should be possessed by vibrating rollers are the following:—They should revolve continuously 20 with the revolution of the inking rollers, they should have a reciprocating movement along the faces of the inking rollers, they should be prevented from side slips along the faces of the inking rollers, they should be easily 25 moved from contact with the inking rollers when desired for cleaning or repairing purposes and be capable of retention in such non-contact position, they should be easily removed from and inserted into the press mechanism, they should be positive in action. 30

The device of my invention possesses all of the above mentioned and other desirable properties as will be evidenced from a consideration of my specification and its accompanying drawings.

In the accompanying drawings illustrating modified forms of the device of my invention, similar parts are designated by similar numerals.

- 40 Figure 1 is a perspective view of my device applied to a printing press.

Figure 2 is a broken top view of one form of my device, partly broken away for purposes of explanation.

- 45 Figure 3 is a cross-section through the line 3—3 of Figure 2.

Figure 4 is a longitudinal-section through the line 4—4 of Figure 2.

- Figure 5 is a cross-section through the line 50 5—5 of Figure 2.

Figure 6 is a cross-section through the line 6—6 of Figure 2.

Figure 7 is a cross-section through the line 7—7 of Figure 2.

- 55 Figure 8 is a cross-section through the line 8—8 of Figure 5.

Figure 9 is a top view of a modified form of housing.

Figure 10 is a cross-section through the line 10—10 of Figure 9.

The particular form of the device of my invention shown in the accompanying drawings comprises a hollow roller 10, through which passes a tubular shaft 11, supported by the bearing 12 and reduced end portion 13 of the roller 10. Revoluble upon and slideable upon the shaft 11 is an externally threaded hollow spindle 14. The interior end 15 of the spindle 14 is angularly faced or cam edged. Transversely movable upon the shaft 11 is a cam, or clutch, member 16, one end face of which is angularly abuttable upon the end 15 of the spindle 14. The cam member 16 has a plurality of slots 17, 17. A coiled spring 19 is maintained under tension between the clutch 16 carried by the hollow shaft 11 and the pin 20 carried by the shaft 11. The interior thread of the end flange 13 of the roller 10 meshes with the threaded spindle 14.

If the shaft 11 be retained from revolution, and the roller 10 be revolved, the spindle 14 will be maintained in non-revolvable position upon the shaft 11 and the meshment member 13 with the threads of the spindle 14 will cause the roller 10 to have a transverse movement along the shaft 11. When the pin 21' of the member 13 reaches and abuts upon the stop-pin 21 and the revolution of the roller 10 around the spindle 14 is prevented, the spindle 14 and the roller 10 will revolve together around the shaft 11 because of the engagement of the pin 21 with the pin 21' carried by the end member 13. Similarly, when the pin 21' of the member 13 reaches and abuts upon the pin 22, the spindle 14 and the roller 10 will revolve together upon the shaft 11.

It will thus be seen that the tension of the spring 19 and the abutment of the two cam, or inclined faces, of the members 15 and 16 maintain the spindle 14 from revolution while the roller 10 is capable of revolution around the spindle during its transverse movement, but when this transverse movement is prevented, the roller 10 and the spindle 14 revolve together. This is a most important attribute of a device of this character as it insures the constant revolution of the roller during its use.

Within one end of the shaft 11 and fixedly attached thereto by the pins 23, 23 is an eccentrically positioned end support 24 having a longitudinally positioned slot 25. The sup-

port 24 has the stop-pin 26 and the operating member 27, both integral with the support 24.

Within the other end of the shaft 11 and fixedly attached thereto by the pins 28, 28 5 is an eccentrically positioned end support 30 having the stop-member 31 integral therewith.

The support for the end support 24 comprises a U-shaped housing 32 having the integral outwardly extended base members 33, 33, the rearward upper face 34 of each base member being inclined downwardly and the forward portion of each base member having a downwardly extended clamping flange 35.

15 A clamping member comprises two U-shaped members 36, 36 each having the extended gripping member 37 and 38. The two U-shaped members are connected by the integral rib 39, and the gripping members 38, 38 are connected by the integral flange 40. There is thus formed a clamping member having two upper spaced gripping members and two lower gripping members. Each upper gripping member 37 has a rearwardly 25 inclined threaded hole 41, within which is a threaded set-screw 42 having an angular opening 43 longitudinally therein.

Pivotedly carried within the housing 32 of the end support 24 at 44 is a locking member 30 45 having the key 46 and the thumb piece 47. The key 46 is held in normal position by the spring 48.

To attach the housing to the roller supporting bracket 49 of a printing machine, the 35 housing 32 is placed upon the upper face of the bracket 49, the clamping flanges 35, 35 extending over the side face thereof. The clamping member is then placed upon the opposite side of the bracket 49 with the gripping members 37, 37 extended over the base 34, 34 and the gripping members 38, 38, resting against the under face of the bracket 49. An angular tool is then placed in the holes 43, 43 of the set screws 42, 42 and the set-screws 45 screwed inwardly, the interior ends 40 of the set-screws being inserted in the inclined recesses 50, 50 of the base members 34, 34. The inclined movement of the set-screws 42, 42 draws the clamping flanges 35, 35 into contact with the inward face of the bracket 49 and the gripping members 38, 38 into contact with the lower face of the bracket 49, the one movement of the set-screws thus causing a firm gripping and connecting 55 means between the housing and the bracket.

The housing of the end support 30 is similar to that above described except that the locking means does not have the key 46, and the lower face of the locking means has an 60 inclined recess 51.

In Figures 5 and 6 the full lines represent the device in disengaged position and the dot-and-dash lines represent it in engaged position.

65 The method of placing the described vi-

brator roller into the printing press is as follows:—The housings are clamped to the brackets as above described. Lift the left hand locking means by means of its thumb piece 47 and slide the end 30 thereunder as far as it will go, the stop member 31 passing thereunder through the recess 51. Then raise the right hand locking means by means of its thumb piece 47 and pass the end 24 thereunder, allowing the key 46 to fit within the slot 24. The device is then in the position shown in Figures 2 and 3. It will then be noted that because of the eccentrically positioned ends 24 and 30, the vibrating roller 10 is in raised position and hence out of contact with the inking rollers 53, 53.

To place the vibrating roller 10 in operating position, that is in contact with the inking rollers 53, 53, it is revolved 180° by lifting key 46 from slot 25. It is removed by 85 disengaging roller first, then lifting thumb piece 47 at end 30, drawing 30 under the cam until end 24 clears housing and then pulling roller out to the right.

It will be noted that the device is held free 90 from transverse movement in both operative and inoperative positions.

The modified form of housing shown in Figures 9 and 10 comprises the housing 60 having the opening 61 and clamped to the bracket 49 by means of the bolts 62, 62. The housing has the extended hollow portion 63 within which is a locking member, or key, 64, controlled by the spring 65 and having the exterior thumb push member 66. Each 100 end 67 of the shaft 11 has a hole 68 therein into which the key 64 may be inserted to lock the shaft 11 from transverse and rotational movement.

It will be noted from the above that the 105 cam movement of the spindle 14 operates to insure a constant revolution of the vibrating roller even when it abuts upon the side of the device and is prevented from further transverse movement.

It will be further noted that the vibrating 110 roller of my invention is readily placed in an operative position and so maintained, that it is free from side-slip and that it can be easily removed from and inserted within the printing press.

I do not limit myself to the particular size, shape, number, arrangement or material of parts as shown and described as these are given simply as a means for clearly explaining the device of my invention.

What I claim is:—

1. In a vibrating roller, in combination, a shaft having its ends offset, a housing for each end of said shaft, means capable of locking said shaft in its lowered and raised positions, means whereby said shaft may be unlocked from its lowered position allowing its revolution to raised position without removal from said housings, said shaft being 125 130

removable from said housings without disconnecting the elements of said housings, a roller carried by said shaft, means for revolving said roller and means for imparting 5 a reciprocating movement to said roller during its revolution.

2. In a vibrating roller, in combination, a shaft having its ends offset, one offset end having a longitudinal slot therein, a housing 10 for each end of said shaft, means capable of locking said shaft in its lowered and raised positions, means whereby said shaft may be unlocked from its lowered position allowing its revolution to raised position without re- 15 moval from said housings, said shaft being removable from said housings without disconnecting the elements of said housings, a roller carried by said shaft, means for revolving said roller and means imparting a re- 20 ciprocating movement to said roller during its revolution.

3. In a vibrating roller, in combination, a shaft having its ends offset, one offset end having a longitudinal slot therein, a housing 25 for each end of said shaft, means capable of removably attaching said housings to brackets, means capable of locking said shaft in its lowered and raised positions, means whereby said shaft may be unlocked from its lowered 30 position allowing its revolution to raised position without removal from said housings, said shaft being removable from said housings without disconnecting the elements of said housings, a roller carried by said shaft, means for revolving said roller and means for imparting a reciprocating movement to said roller during its revolution. 35

4. In a vibrating roller, in combination, a shaft having its ends offset, one offset end 40 having a longitudinal slot therein, a housing for the unslotted end having a recess within which said shaft is longitudinally movable, a second housing for the slotted end having a recess therein within which said shaft is lon- 45 gitudinally movable, locking means carried by said second housing preventing the revolution of said shaft therein, means whereby said shaft may be unlocked from non-revo- lution allowing its revolution without remov- 50 al from said housings, a roller carried by said shaft, means for revolving said roller

and means for imparting a reciprocating movement to said roller during its revolution.

5. In a vibrating roller, in combination, a shaft having its ends offset, one offset end having a longitudinal slot therein, a housing for the unslotted end having a recess within which said shaft is longitudinally movable, a second housing for the slotted end having a recess therein, within which said shaft is longitudinally movable, means capable of removably attaching said housings to brackets, spring operated locking means carried by said second housing preventing the revolution of said shaft therein, means whereby said shaft may be unlocked from non-revolution allowing its revolution without removal from said housings, said shaft being removable from said housings without disconnect- 65 ing the elements of said housings, stop pins limiting the longitudinal movement of the shaft within the housings, a roller carried by said shaft, means for revolving said roller and means for imparting a reciprocating 70 movement to said roller during its revolution. 75

6. In a vibrating roller, in combination, a shaft having its ends offset, one offset end having a longitudinal slot therein, a housing for the unslotted end having a recess within which said shaft is longitudinally movable, a second housing for the slotted end having a recess therein within which said shaft is lon- 80 gitudinally movable, means capable of removably attaching said housings to brackets, spring operated locking means carried by said second housing placeable within said slot preventing the revolution of said shaft therein, means whereby said shaft may be unlocked from non-revolution allowing its rev- 85 olution from lowered to raised position without removal from said housings, said shaft being removable from said housings without disconnecting the elements of said housings, stop pins limiting the longitudinal move- 90 ment of the shaft within the housings, a roller carried by said shaft, means for revolving said roller and means for imparting a reciprocating movement to said roller during its revolution. 95

LOUIS HALPERN.
